2,168,340

METHOD OF AND APPARATUS FOR
GROOVING WIRECharles K. Hill, Cleveland, Ohio, assignor to The
Hillwood Manufacturing Company, Cleveland,
Ohio, a corporation of Ohio

Application December 24, 1936, Serial No. 117,496

8 Claims. (Cl. 80—10)

This invention relates, as indicated, to methods of and apparatus for grooving wire, but has reference more particularly to the grooving of wire for the purpose of providing stock from which spiral-groove nails may be formed.

It has heretofore been proposed to manufacture nails having spiral grooves and ribs, as a result of which the nail, after being driven into the parts to be secured together, could not be withdrawn by a direct longitudinal pull, but could only be withdrawn by a turning movement of the nail during the pulling thereof.

The principal difficulty attending the manufacture of such nails was that of imparting to the wire from which the nails were formed grooves and ribs of uniform pitch. Furthermore, due to the method by which such nails were manufactured, they could be produced in limited quantities only and at a cost which made the general use thereof prohibitive.

It is a primary object of the present invention to provide a novel method and apparatus whereby nails having spiral grooves and ribs of uniform pitch can be manufactured in commercial quantities and at a cost not appreciably in excess of the cost of ordinary nails made from wire of the same size.

Another object of the invention is to provide a method of forming grooves and ribs in wire for use in making nails of the aforesaid character, which method is continuous and requires a minimum of attention on the part of the operator.

A further object of the invention is to provide apparatus for practicing the aforesaid method which is positive in operation and adapted for the grooving or ribbing of wire of various diameters and for the production of grooves and ribs of various pitches.

To the accomplishment of the foregoing and related ends, said invention, then, consists of the means hereinafter fully described and particularly pointed out in the claims, the annexed drawings and the following description setting forth in detail certain means and one mode of carrying out the invention, such disclosed means and mode illustrating, however, but one of various ways in which the principle of the invention may be used.

In said annexed drawings—

Fig. 1 is a plan view of the apparatus for grooving wire for use in manufacturing nails in accordance with the invention; Fig. 2 is a side elevation of the apparatus shown in Fig. 1; Fig. 3 is a fragmentary longitudinal cross-sectional

view, taken on the line 3—3 of Fig. 1; Fig. 4 is a front elevation of the wire grooving device, with the cover removed to more clearly show the arrangement of the grooving disks; Fig. 5 is an enlarged view of a nail made from wire grooved in accordance with the invention; and Fig. 6 is a further enlarged transverse cross-sectional view of the nail, taken on the line 6—6 of Fig. 5.

Referring first to Figs. 5 and 6, a nail manufactured in accordance with the present invention consists, as shown, of a head 1 and shank 2. The shank 2 has formed therein a plurality of spiral grooves 3, 4, 5 and 6, extending longitudinally of the nail and arranged a quarter turn apart. In the formation of each of these 15 grooves, a grooving disk is employed which displaces metal laterally to form at one edge of the groove a rib extending outwardly from the surface of the nail, such rib terminating in a fairly sharp edge. The ribs are designated by reference numerals 7, 8, 9 and 10. As the nail is driven, the spiral ribs engage the wood and produce a rotary movement of the nail as it is forced into the wood, the portion of the wood compressed by the ribs being forced into the grooves 25 and thereby forming, when the nail is driven, complete keys precluding longitudinal movement of the nail.

Nails, as thus described, are manufactured by the usual heading, pointing and cutting operations from long coils of wire which have previously been spirally grooved and ribbed by a continuous method and by means of apparatus which will now be described. The apparatus for grooving and ribbing the wire is best shown in 35 Figs. 1 to 4, inclusive.

Referring to Figs. 1 and 2, there is illustrated a table 11 having supporting legs 12. Mounted on the table at suitably spaced points are bearings 13, 14 and 15, in which is journalled a shaft 40 consisting of sections 16 and 17 rigidly secured to each other and respectively provided with aligned axial passages 18 and 19.

Threadedly secured to the forward end of the shaft section 16 is a hub plate 20, which is locked 45 in position on such shaft section by means of a lock nut 21. Secured to this hub plate, as by means of cap screws 22, is a chuck 23 having an annular flange portion 24 of slightly reduced external diameter extending from the front face 50 thereof, and which is interrupted to provide a plurality of radially extending passages 25. In the present embodiment of the invention, four such passages are provided, although as will presently become apparent, a larger or smaller 55

number of passages may be provided, depending on the number of grooves and ribs which it is desired to simultaneously form in the wire.

Mounted in each of the passages 25 for slide-
5 ble movement radially of the flange 24 is a disk
holder 26. Each disk holder is in the form of a
hollow block having a wall 27, the radially out-
ward surface 28 of which tapers slightly from
10 front to rear but is arcuately curved in a direc-
tion transverse to the front to rear direction, as
clearly shown in Fig. 4. The radially inner end
15 of the disk holder is provided with spaced trun-
nion portions 30 having seats for the reception
of a pin or shaft 31, the axis of which is inclined
with respect to the general plane of the chuck
23. The pin 31 has rigidly secured thereto a
20 grooving disk 32, which is freely revoluble in its
holder, and the peripheral edge of which is of
V-shaped cross-section.

20 For the purpose of maintaining the holders
26 in their radially outermost position, the chuck
23 is provided with pins 33 which serve as seats
25 for springs 34, which bear against the walls 27
of the holders. The radially outward movement
25 of the holders is limited by an annular band 35
which is threadedly secured to the chuck 23, and
engages the surfaces 28 of the holders. The inner
30 surface 36 of this band is tapered from front
to rear to correspond with the taper of the sur-
faces 28 of the holders, so that upon rotation
of the band, the holders will be simultaneously
35 adjusted. This adjustment is permitted by rea-
son of a clearance space 29, which is provided
between the radially outward surface of the
flange 24 and the inner surface 36 of the band
35. It will be apparent from the foregoing that
radial adjustment of the grooving disks for the
purpose of grooving wire of various diameters
may be easily accomplished by the simple ex-
40 pedient of rotating the band 35 towards or away
from the chuck 23. To facilitate such rotation,
the band is provided in its outer peripheral sur-
face with sockets 37 for the reception of a
wrench or other tool.

45 Secured to the flange 24 of the chuck is a cover
plate 38, to which in turn is threadedly secured a
spider 39, the hub of which has secured therein
a guide 40 for passage of the wire W to be grooved
and ribbed.

50 The chuck 23 and associated elements are pos-
itively rotated by mechanism comprising an elec-
tric motor 41, pinion 42, gear 43 and shaft 16—
17. The speed of the chuck may be varied, for
which purpose an extra gear 44 is provided.

55 In addition to the grooving apparatus proper,
which has been described, there is mounted on
the table 11 a take-up reel or drum 45 for the
grooved wire, which drum is mounted for rota-
60 tion about a vertical axis and driven in syn-
chronism with the grooving apparatus by mech-
anism comprising a worm 46 which is keyed to
the shaft section 17, worm gear 47, bevel gears
48 and 49, shaft 50, bevel gears 51 and 52, ver-
65 tical shaft 53, and clutch section 54. The drum
is of standard construction and need not be
further described.

The operation of the apparatus will now be
described:

70 The wire W, which is to be grooved and which
is in the form of a coil, is mounted on a feed
reel or drum (not shown) and is passed through
the guide 40 and passages 18 and 19 in the shaft
sections 16 and 17, the leading end of the wire
being then secured to the take-up drum 45. The
75 motor 41 is then started, causing the chuck 23

and associated parts to be positively rotated, and
at the same time, the take-up drum 45 is posi-
tively rotated to pull the wire through the groov-
ing head and receive the convolutions of such
wire. As the wire travels through the space be-
tween the grooving disks 32, the disks being free-
ly rotatable about their axes, rotate about the
80 wire, the peripheral edges of the disks being
forced into the wire, thereby forming the spiral
grooves 3, 4, 5 and 6, and incidentally to the
formation of such grooves, the spiral ribs 7, 8, 9
and 10, respectively adjacent thereto. The take-
up drum rotates at a speed sufficient to maintain
tautness in the wire, and the linear speed of the
85 wire is maintained constant by virtue of the
fact that the grooved wire always contacts first
with the lower or widest portion of the drum.
This is possible because the preceding coils of
wire continually slip upward and away from the
lower portion of the drum and onto the narrower
90 portions, since the drum is tapered for this pur-
pose. Consequently, instead of winding the wire
in layers one over the other with a constantly
increasing winding diameter which would in-
crease the speed with which the wire is drawn
95 through the apparatus, the wire is always wound
on a surface of the same diameter and is pulled
through the apparatus at the same linear speed.
In this way, it is not necessary to change the
speed of rotation of the drum to compensate for
100 an increasing diameter of bundle, but the drum
can be rotated at a constant peripheral speed
while pulling the wire through the apparatus at
a constant linear speed.

For a given angular setting of the grooving
disks, that is, for a given pitch of the grooves
and ribs, a definite and predetermined ratio be-
tween the speed of the take-up drum and the
speed of the grooving head is maintained. The
105 speeds of the drum and head may, however, be
increased when it is desired to increase the pro-
duction of grooved wire. In order to vary the
pitch of the grooves and ribs, it is necessary to
substitute for the holders 26 other holders hav-
ing grooving disks set at a different angle to the
110 general plane of the chuck than that shown, in
which event, a different ratio between the speeds
of the grooving head and take-up drum must be
established, depending on the new angle. In or-
der to establish a different ratio between the
115 speeds of the grooving head and take-up drum,
the bevel gears 48 and 49 are replaced by other
gears.

Due to the constant linear speed of the wire
and the positive rotation of the grooving head,
120 a coil of wire is formed in which the pitch of
the spiral grooves and ribs is absolutely uniform
and unvarying from one end of the coil to the
other. The coil of wire, thus formed, is then
used to manufacture nails by the usual heading,
125 pointing and cutting operations, the finished nail
being shown in Fig. 5.

During the grooving operations, a certain
amount of heat is generated within the grooving
head, and for the purpose of dissipating this heat
130 and ventilating the head, the spider 39 may be
provided with fan blades 55.

After the entire coil of wire has been thus
grooved, the motor is stopped and at the same
time, a braking element 56 is applied to the drum
135 by means of a lever 57. The coil of grooved
wire is then removed from the drum. The drum
may then be reset to any desired position by first
disengaging the clutch section 54 from the drum,
as by means of a lever 58.

Other modes of applying the principle of my invention may be employed instead of the one explained, change being made as regards the means herein disclosed, provided those stated by 5 any of the following claims or their equivalent be employed.

I therefore particularly point out and distinctly claim as my invention—

1. A method of preparing stock for spiral-grooved nails which comprises continuously unwinding wire from a roll, imparting to said wire throughout its length a spiral groove, and winding the grooved wire on a drum having a tapered surface.

15 2. A method of preparing stock for spiral-grooved nails which comprises continuously unwinding wire from a coil, pressing wire-grooving means against the surface of the unwound wire, and winding the grooved wire on a drum 20 having a tapered surface, whereby a spiral groove of uniform pitch is formed in the surface of said wire substantially throughout the length thereof.

3. A method of preparing stock which comprises continuously unwinding wire from a coil, 25 rotating a wire-grooving disk about the unwound wire, with the disk engaging the wire, and winding the grooved wire on a drum having a tapered surface, whereby a spiral groove of uniform pitch is formed in the surface of said wire substantially throughout the length thereof.

30 4. Apparatus for grooving wire which comprises means for positively moving said wire at a constant linear speed, said means including a take up drum having a tapered surface, means rotatable about said wire for grooving the same as it is thus moved, and power-driven means for rotating said last-named means.

5. Apparatus for grooving and ribbing wire which comprises means for positively moving

said wire at a constant linear speed, said means including a take up drum having a tapered surface, grooving disks rotatable about said wire and operative to simultaneously impart to the surface of said wire spiral ribs, and power-driven means 5 for positively rotating said grooving disks.

6. Apparatus for forming spiral grooves of uniform pitch in the surface of wire of circular cross section, comprising means for exerting a pull on said wire including a take up drum having a tapered surface, means for grooving the wire so pulled, said means comprising a chuck having more than two grooving disks therein, and means for positively rotating said wire-grooving means about the wire as it is pulled by said first-named 15 means.

7. Apparatus for grooving wire, comprising a chuck having radially extending passages therein, holders slidably mounted in said passages, grooving disks journaled in said holders, spring means 20 normally biasing said holders in a radially outward direction, and means for moving said holders against the pressure of said springs in a radially inward direction, said last-named means comprising an annular band in threaded engagement with said chuck and having its inner peripheral surface tapered relatively to the axis of the band, whereby when the band is rotated relatively to said chuck, said holders will simultaneously be forced radially inwardly.

8. Apparatus for grooving wire, comprising a chuck, a plurality of holders slidably mounted in said chuck, grooving disks journaled in said holders, means for rotating said chuck about the wire, and a guide for passage of the wire to be 35 grooved, said guide removably secured to said chuck.

CHARLES K. HILL.
